UNITED STATES PATENT OFFICE.

PAUL THEODOR BEIER, OF RODELHEIM, FRANKFORT-ON-THE-MAIN, GERMANY,
ASSIGNOR TO UNITED SHOE MACHINERY COMPANY, OF PATERSON, NEW
JERSEY, A CORPORATION OF NEW JERSEY.

STITCH-DOWN-SHOE-LASTING MACHINE.

1,152,694.

Specification of Letters Patent.

Patented Sept. 7, 1915.

Application filed December 5, 1913. Serial No. 804,870.

To all whom it may concern:

Be it known that I, PAUL THEODOR BEIER, a subject of the Grand Duke of Baden, residing at Rodelheim, Frankfort-on-the-Main, Germany, have invented certain Improvements in Stitch-Down-Shoe-Lasting Machines, of which the following description, in connection with the accompanying drawings, is a specification, like reference 10 characters on the drawings indicating like parts in the several figures.

This invention relates to machines for use in the manufacture of boots and shoes and in particular to machines for lasting shoes 15 having an extension sole edge upon which an outturned upper flange is secured. Shoes of this type are commonly known as veldtschoen in some parts of Europe and in the United States are usually referred to as 20 stitch-downs.

The present invention seeks to overcome certain objections which have been found to exist in machines heretofore employed for this class of work.

Accordingly, one important feature of the invention lies in the provision, in a machine of the type referred to, of an improved pressing device and a support for the shoe which are so arranged that the shoe may be 30 presented for the described operation thereon of the presser with the upper and presser in full view of the workman, the shoe lying preferably in a slightly upwardly inclined position. This enables the workman 35 closely to observe the progress of the work and accurately to guide the shoe in presenting different portions thereof to the presser.

Another feature of importance is comprised in an improved pressing or forming 40 device which is yieldingly supported for movement, and is actuated preferably in a curved path so as first to engage the shoe upper at a point located a short distance above the edge of the last, and then to press 45 the upper downward and push it into the angle formed by the last edge and the sole, and thereafter to force the upper flange firmly against the surface of the extended sole edge so that it will be pressed flat thereon. The contracting surfaces of the upper flange and the sole edge or either of these 50 parts are preferably coated with cement prior to presenting the shoe to the machine

so that they will adhere and the upper remain in the position to which it has been 55 forced by the action of the pressing device without requiring tacks or similar fastenings.

Another important feature resides in a rotatable work support which is arranged 60 and combined with the pressing device so that the under surface of the extended sole edge is sustained by the support to present successive portions of the upper to the operation of said device as the workman feeds 65 the shoe around; the shoe when in the above-described position having its upper presented in full view of the workman. Preferably the work support is sustained yieldingly upon a spindle or the like in order that 70 the force of the downward blows imparted by the presser may be cushioned, and means are provided to adjust the tension of the yielding means and thus vary the amount of 75 resistance which is offered to the action of the presser. The described work support is shaped to fit within the channel of the shoe sole and has a beveled edge to engage the lip. Preferably an adjustably mounted sole 80 rest is located in front of the rotatable work support to coöperate therewith in properly supporting and positioning the shoe for the operation thereon of the presser.

Another feature of the invention is found 85 in a provision for sustaining the work support for adjustment longitudinally of the machine to position it properly for sole edges of different widths, or degrees of extension. This feature comprises, in the illustrated embodiment of the invention, a 90 slide which carries the work support and is guided for movement in ways mounted upon the work support spindle. A suitable handle is connected through appropriate devices with the slide to effect its adjusting 95 movements.

Other features of the invention including 100 important details of construction and combinations of parts will be hereinafter more particularly described and claimed.

Figure 1 represents a side elevation, partly sectional, of a machine embodying the invention; Fig. 2 is a front elevation, partly in section, of the same machine; Fig. 3 is a detail view showing diagrammatically 105 the fore part of a shoe in position for oper-

ation thereon by the elements of the machine, and Fig. 4 is a detail.

The head 1 of the machine is mounted upon a suitable pedestal, and carries bearings 5 for the driving shaft 2. Said shaft supports a loose pulley 5 and also has rigidly secured to its outer end a clutch member 6 having a cone face to coöperate with a cone face formed interiorly of the loose pulley 5, 10 a spring 66 normally holding said clutch parts separated. A treadle rod 4 carries a wedge which engages a wedge surface acting against the loose pulley and moves said pulley along the shaft to effect engagement of 15 the clutch members for imparting rotation to the driving shaft when the workman steps on the treadle connected to rod 4, while a reverse movement of the loose pulley will cause a disengagement of said members and 20 stop the rotation of the shaft when the treadle is released.

The shaft 2 carries at its inner end a disk 7 having a crank pin to which is joined a pitman 8 having connection at its opposite 25 end through a pin 9 with a cross-head 10. The cross-head is guided for vertical reciprocating movements in the machine head by the rods 110 which fit bores in the cross-head. A bell-crank lever 12 is pivotally 30 supported by a pin 11 on the cross-head. The bell-crank lever has vertical arms to the lower portions of which is pivoted the rear end of a presser-foot 13, having below the front end a flat surface 130, as shown. 35 The bell crank 12 and presser-foot 13 are provided, respectively, with stops 131 and 132, for limiting the amount of upward yielding movement of the presser foot as it turns about the pivot 38 when operating 40 upon a shoe upper. Intermediate its ends the presser foot is pivoted to a rod 16 which passes freely through a block having trunnion connections 36 with the forward short arms of the bell-crank 12, so as to swing 45 freely thereon, and a spring 15 is confined between the block and the presser foot. The rod 16 has a stop nut 37 threaded thereon through which the tension of spring 15 may be adjusted, and hence the amount of resistance offered by the spring to the upward 50 swinging movement of the presser-foot, controlled.

The pivot 38 connecting the lever 12 with the presser-foot carries rolls 40 which run 55 in cam-ways 14, 14, formed in the machine frame on opposite sides of the presser-foot. These ways are shaped to cause a forward movement of the presser-foot during the first portion of the downward movement 60 which the foot receives from the cross-head 10, and as the result of these two movements the end of the foot moves in the curved path indicated in Fig. 3 by a broken line. During the remaining portion of the downward 65 movement of the foot the rolls 40 pass into

the slightly backwardly inclined portions of the grooves 14 which cause a reverse movement of the foot.

The frame 1 is provided with vertical guideways 117, 117, which receive a slide 17. 70 This slide has a spindle 18 which passes through a sleeve 23, having threaded engagement with the frame of the machine and carrying a set nut to hold the sleeve in that position to which it has been moved through 75 such engagement. The lower end of the spindle 18 is threaded and a clamp nut 19 is secured thereon and bears against the lower end of the sleeve 23. A spiral spring 22 is confined between a collar above the sleeve 80 and the slide 17, and yieldingly sustains the work-supporting wheel 30 against the impactive force of the presser-foot when the latter contacts with a shoe sole on said support. The tension of the spring 22 is adjustable by means of the nut 19 on rod 18, and the height of the work-supporting devices, as an entirety, may be adjusted by moving the sleeve 23 up or down in the frame, the sleeve being held in its different 85 positions of adjustment by the set nut.

By adjusting the tension of the spring 22 the amount of yielding resistance offered to the blows of the presser-foot can be controlled to meet varying conditions of the 90 stock, while the adjustments of the height of the work-supporting wheel will enable the operator to position shoes of different sizes and styles in the correct vertical relation to the presser-foot.

The slide 17 has horizontal guide-ways 37 within which slides a block 35 having a vertical pivot thereon to rotatively sustain a work supporting wheel or disk 30. This wheel has a beveled upper surface to fit 105 within the channel of a shoe sole, and a peripheral beveled portion 32 to fit the inner surface of the channel lip as shown in Fig. 3. By this construction the sole edge will be guided accurately through the engagement 110 of the sole with the wheel as the operator feeds the shoe along to present successive portions of the upper to the action of the presser-foot. The block 35 also carries, in front of the wheel 30, the sole supporting pin 31 which is adjustable in height through a set screw, as shown by dotted lines in Fig. 1, 115 and is adapted to engage beneath a shoe sole inside of the lip as shown in Fig. 3, and thus coöperate with the wheel 30 in supporting the shoe in position for operation thereon by the presser-foot. Movement of the block 35 in the ways 37 to adjust the position of the work-supporting wheel 30 and pin 31 appropriately for shoes having soles of different widths may be effected 120 conveniently through a knob or handle 20 carrying a crank pin which is connected by a link 21 with the block. Rotation of the handle 20 in one direction will effect a for-

ward movement of the block to position a shoe having a sole with a given width of extension with its upper in proper position for the operation of the presser, while a reverse movement of the handle will move the block rearwardly to position a shoe whose sole extension is of less width, in correct position for operation thereon by the presser.

In the use of the machine a shoe comprising a sole which is usually tacked to the last, and an upper which may be in suitable temper and has been fitted over the last, is presented to the machine as shown in Fig. 3, the rotatable work-supporting wheel 30 engaging beneath the sole and fitting within the channel and against the lip by its two beveled surfaces and the sole support 31 engaging the sole to the rear of the lip. Either the upper surface of the sole edge, the lower face of the upper which contacts therewith, or both of these parts, are coated with cement prior to assembling the shoe. The shoe when thus positioned presents its upper portion to the workman who may thus clearly observe the progress of the work. When the treadle is depressed the brake will be withdrawn and the wedging surfaces on the treadle rod and loose pulley will act to force the clutch members into engagement to start the rotation of the driving shaft. Through the previously described connections between the shaft and cross-head 10 the latter will be reciprocated and upon each downward movement the presser-foot will be caused to travel downwardly and forwardly in a curved path, its forward end meeting the shoe upper at a point above the edge of the last and pressing it downward and snugly into the angle formed by the extended portion of the sole and the last. During this movement the foot will yield backward slightly under the influence of the spring 15. Finally by a further downward movement the presser-foot will press the upper flat upon the extended edge of the sole. This operation is repeated rapidly and the workman moves the shoe along to present successive portions of the upper to the presser-foot, the work-supporting wheel turning about its axis as the shoe is thus fed and serving to support the shoe, while guiding it and maintaining the sole edge at all points the same distance from the presser-foot. The sole support 31 also acts in conjunction with the wheel to properly support the shoe as the shoe is fed along by the workman. As the sole flange is pressed flat upon the upper face of the sole the cement on the contacting surfaces of these parts will cause them to adhere and thus, without the aid of tacks, will hold the upper in substantially the position to which it has been forced by the presser-foot. By reason of the fact that the tool moves in a curved path over the shoe edge such movement will

serve to stretch the upper and mold it to the shape of the last, and as the point of the tool enters the crease formed at the point where the sole and last meet the upper will be forced into the crease and a sharp angle formed thereby with the upper flange that overlies the sole. It will also be seen that the flange of the upper will be pressed against the sole in a very effective manner by the flat portion 130 of the presser so as to adhere to the sole throughout every portion of its contacting surface.

Having thus described my invention, what I claim as new and desire to secure by Letters Patent of the United States is:—

1. In a machine of the class described, the combination with means for supporting a shoe with its sole slightly inclined to a horizontal plane and its upper presented toward the workman as he stands in front of the machine, of a shoe forming tool constructed and arranged to engage the upper at a point above the edge of the last and force it into the angle between the side of the last and a projecting portion of the shoe sole, and actuating means for said tool.

2. In a machine of the class described, the combination with means for supporting a shoe with its sole slightly inclined to a horizontal plane and its upper presented toward the workman as he stands in front of the machine, of a shoe forming tool arranged for movement in a downwardly curved path about the side of a last for molding the upper to the side of the last and tucking it into the angle between the edge of the last and a projecting portion of the sole, and actuating means for said tool.

3. In a machine of the class described, the combination with means for supporting a shoe with its upper presented toward the workman as he stands in front of the machine, of a shoe forming tool arranged for movement in a curved path to mold the upper to the side of the last and tuck it into the angle between the edge of the last and a projecting portion of the sole and constructed to press the marginal portion of the upper firmly against the sole, and actuating means for said tool.

4. In a machine of the class described, the combination with a rotatable work support constructed to engage beneath the outer edge portion of a shoe sole, of a shoe forming tool and actuating mechanism for causing the tool to engage the upper at a point above the edge of the last and force it downwardly along the side of the last and into the angle between the last edge and a projecting portion of a shoe sole.

5. In a machine of the class described, the combination with a rotatable support constructed to engage the channel lip of a shoe sole and guide the shoe, of a shoe forming tool and actuating mechanism to cause the

- tool to mold the upper to the side of the last and tuck it into the angle between the edge of the last and a projecting portion of the sole.
6. In a machine of the class described, the combination with a rotatable work support constructed to engage the channel lip of a shoe sole and a coöperating support for engaging the sole back of the lip, of a shoe forming tool and actuating mechanism to cause the tool to tuck the upper into the angle between the edge of the last and a projecting portion of the sole.
7. In a machine of the class described, the combination with a shoe forming tool having a flattened foot at its end, of actuating mechanism for causing movement of the tool in a path curved downwardly and forwardly with its concave side toward the operator as he stands in front of the machine to mold a shoe upper to the side of the last and tuck it into the angle formed by the edge of the last and a projecting portion of the sole, and thereafter causing said foot to press the upper flange firmly against said projecting portion of the sole.
8. In a machine of the class described, the combination with a shoe forming tool, and actuating mechanism including a yielding element for moving the tool in a downwardly curved path having its concave side toward the operator as he stands in front of the machine to cause the tool to mold a shoe upper to the side of the last and force it into the angle between the edge of the last and an extended portion of the sole and press the sole-attaching flange of the upper firmly against the sole.
9. In a machine of the class described, the combination with means for supporting a shoe with its sole slightly inclined to a horizontal plane and its upper presented in full view of the workman, of a yieldingly-actuated tool constructed and arranged for downward movement to mold the upper to the side of the last and press it into the angle formed between the edge of the last and a projecting portion of the sole.
10. In a machine of the class described, the combination with a shoe forming tool, of means including a cam-way for causing the tool to travel in a downwardly curved path having its concave side toward the operator as he stands in front of the machine to mold a shoe upper to the side of the last and press it into the angle between the last and an extended sole edge, and means for actuating the tool.
11. In a machine of the class described, the combination with a support, of a shoe forming tool carrying a roll, a cam-way to receive the roll and guide the tool in a downwardly curved path having its concave side toward the operator as he stands in front of the machine for molding a shoe upper to the

side of a last on said support, and means for actuating said tool.

12. In a machine of the class described, the combination with a support arranged to present a shoe with its sole slightly inclined to a horizontal plane and its upper toward the operator as he stands in front of the machine, of a shoe forming tool carrying a roll, a cam-way to receive the roll and guide the tool in a curved path for molding a shoe upper about the side of a last on said support, and means for yieldingly actuating said tool.

13. A machine for use in making stitch-down shoes having, in combination, a reciprocating head, a carrier connected to the head, a tool pivoted at one end to the carrier, and a cam-way for guiding the tool about the edge of a shoe to mold the upper to the side of the last.

14. A machine for use in making stitch-down shoes having, in combination, a reciprocating head, a carrier pivotally connected to the head, a tool pivoted to the carrier and carrying a roll, and a cam-way to receive the roll and guide the tool in a curved path for molding the upper to the side of a last.

15. A machine for making stitch-down shoes having, in combination, a reciprocating head, a carrier pivotally connected to the head, a shoe forming tool having pivotal connection at one end with the carrier and carrying a roll, a cam-way to receive the roll, and means yieldingly connecting the carrier with the tool at a point between the roll and the operative end of the tool.

16. A machine for making stitch-down shoes having, in combination, a reciprocating head, a carrier pivotally connected to the head, a shoe forming tool having pivotal connection with the carrier and carrying a roll, a cam-way to receive the roll, a spring connecting the carrier with the tool for permitting the tool to yield, and means for limiting the extent of the yielding movement of the tool.

17. A machine for making stitch-down shoes having, in combination, a reciprocating head, a carrier pivotally connected to the head, a shoe forming tool having pivotal connection with the carrier and carrying a roll, a cam-way to receive the roll, a spring connecting the carrier with the roll for permitting yielding movements of the tool, and means for varying the tension of said spring.

18. A machine of the class described having in combination, a reciprocating head, a bell-crank lever pivotally connected to the head, a shoe forming tool having pivotal connection with one arm of said lever and carrying a roll, a cam-way to receive the roll, a block pivotally connected with the other arm of said lever, a rod extending through said block and connected with said tool, and a spring surrounding said rod and

confined between said tool and block for permitting backward yielding movement of the tool.

19. A machine of the class described having, in combination, a reciprocating head, a bell-crank lever pivotally connected to the head, a shoe forming tool having pivotal connection with one arm of said lever and carrying a roll, a cam-way to receive the roll, 5 a block pivotally connected with the other arm of said lever, a rod extending through said block and connected with said tool, a spring surrounding said rod and confined between said tool and block for permitting 10 backward yielding movement of the tool, and means for limiting the extent of said movement.

20. In a machine of the class described, the combination with a shoe forming tool, 20 of actuating means for causing the tool to mold an upper to the side of the last and tuck it into the angle between the last and a projecting portion of a sole, and means for supporting a shoe in position for operation 25 thereon by the tool, said means having provision for adjustment to position shoes having sole edges of different degrees of extension, in proper relation to said tool.

21. In a machine of the class described, 30 the combination with a shoe forming tool and actuating means therefor, of shoe supporting means constructed to engage the channel lip of the shoe sole and capable of adjustment toward and from the tool in substantial parallelism with plane of the 35 sole to position shoes having sole-extensions of different widths in proper relation to the tool.

22. In a machine of the class described, 40 the combination with a tool for lasting stitch-down shoes and actuating means therefor, of a shoe support constructed to engage the channel lip of the shoe sole and mounted for adjustment longitudinally of 45 the machine, and means to effect said adjustment.

23. In a machine of the class described, the combination with a shoe forming tool and actuating means therefor, of a guideway 50 extending longitudinally of the machine, a slide mounted therein and sustaining a shoe-support, and means for adjusting the slide to position a shoe on the support in proper relation to the tool.

24. In a machine of the class described, the combination with a shoe forming tool and actuating means therefor constructed and arranged to move the tool downward in a curved path and to tuck a shoe upper into 60 the angle between the edge of a last and the extended portion of a sole and press the sole-attaching upper flange against the sole, of yielding means for sustaining a shoe in operative relation to said tool.

25. In a machine of the class described,

the combination with a shoe forming tool and actuating means therefor constructed and arranged for yielding movements about the side of a last to mold the upper thereto, and to tuck the upper into the angle between 70 the last edge and a projecting portion of the sole and press the sole-attaching upper flange against the sole, of yielding means for supporting a shoe in operative relation to the tool, and provisions for varying the resistance offered by said means to the action 75 of the tool.

26. In a machine of the class described, the combination of a tool for use in lasting stitch-down shoes, actuating means for said 80 tool, a rotatable work rest for engaging beneath the edge portion of a shoe sole to support the shoe in operative relation to the tool, and a coöperating support for engaging the sole at a point to the rear of said 85 work rest.

27. In a machine of the class described, the combination of a tool for use in lasting stitch-down shoes, actuating means for said 90 tool, a rotatable work rest for engaging beneath the edge portion of a shoe sole to support the shoe in operative relation to the tool, and a coöperating adjustable support for engaging the sole at a point to the rear 95 of said work rest.

28. In a machine of the class described, the combination of a tool for use in lasting stitch-down shoes, actuating means for said 100 tool, a rotatable work rest for engaging beneath the edge portion of a shoe sole to support the shoe in operative relation to the tool, and a coöperating support for engaging the sole at a point to the rear of said work rest, said shoe supporting devices being adjustable toward and from the tool. 105

29. A machine for lasting stitch-down shoes having, in combination, a tool and actuating mechanism for the tool constructed and arranged to move it in a downwardly and forwardly curved path about the side of a shoe to mold the upper to the last and tuck it into the angle between said last and the sole edge, and means for supporting the shoe with its sole slightly inclined to a horizontal plane for the operation of said tool. 110

30. A machine for lasting stitch - down shoes having, in combination, a tool, actuating means to impart a downward movement to the tool, and guiding means to cause the tool to move forward, whereby its resultant path of movement is curved downwardly and forwardly with the concave side of said path toward the front of the machine. 120

31. A machine for lasting stitch - down shoes having, in combination, means for supporting a shoe with its sole face downward and its upper toward the operator, a tool, actuating means to impart a downward movement to said tool, and guiding means 125

to cause the tool to first move forward while molding the upper to the curved side of the last, to then press the margin of the upper against the sole, and thereafter to move re-
5 versely while in engagement with the upper flange.

In testimony whereof I have signed my

name to this specification in the presence of two subscribing witnesses.

PAUL THEODOR BEIER.

WALLACE ELLISON.

Copies of this patent may be obtained for five cents each, by addressing the "Commissioner of Patents, Washington, D. C."

It is hereby certified that in Letters Patent No. 1,152,694, granted September 7, 1915, upon the application of Paul Theodor Beier, of Rodelheim, Frankfort-on-the-Main, Germany, for an improvement in "Stitch-Down-Shoe-Lasting Machines," an error appears in the printed specification requiring correction as follows: Page 1, line 50, for the word "contracting" read *contacting*; and that the said Letters Patent should be read with this correction therein that the same may conform to the record of the case in the Patent Office.

Signed and sealed this 14th day of March, A. D., 1916.

[SEAL.]

J. T. NEWTON,

Acting Commissioner of Patents.
